UNITED STATES PATENT OFFICE.

JOHN G. HOMAN, OF STEUBENVILLE, OHIO.

RESISTANCE UNIT.

Application filed November 1, 1921. Serial No. 512,157.

To all whom it may concern:

Be it known that I, JOHN G. HOMAN, a citizen of the United States, residing at Steubenville, in the county of Jefferson, 5 State of Ohio, have invented certain new and useful Improvements in Resistance Units, of which the following is a specification.

This invention relates to an improvement 10 in a resistance unit for use in a rheostat or circuits involving the use of a resistance element.

The primary objects of my invention are to provide a resistance unit of novel construction which can be economically made and assembled, and which may be designed to have a relatively large radiating surface and capacity for heat in proportion to the resistance, and which, therefore, is well 20 adapted for heavy duty.

Other objects are to provide a resistance unit which is simple and rugged, and may be made very compact. The unit may be made in various forms to conform to specified dimensions, and affords flexibility of design without changing the dimensions of the parts.

In carrying out my invention, I propose to employ laminations of material having 30 a relatively high resistance element disposed between the laminæ. It may be in the form of superimposed metal plates having a resistance coating or film thereon, or it may comprise a series of plates of conducting material having separate sheets of a substance of a comparatively highly electrical resistance nature therebetween. The plates or laminæ are in intimate contact with the resistance material in either construction, and serves to conduct the heat therefrom to provide a capacity for the heat and a radiating surface.

My invention may be readily understood from the accompanying drawings, which 45 show somewhat diagrammatically simple embodiments of my invention:

Fig. 1 shows a vertical section through one form of resistance unit;

Fig. 2 shows a horizontal section on line

50 II—II of Fig. 1;

Fig. 3 indicates a plan view of one of the plates or laminæ;

Fig. 4 is a view corresponding to Fig. 1 of a modification;

55 Fig. 5 is a section on line V—V of Fig. 4;

Fig. 6 is a vertical section through a unit showing another modification;

Fig. 7 is a section on line VII—VII of Fig. 6.

Referring to Figs. 1 to 3 inclusive of the drawings, A—A indicates clamping plates on the outside of the unit. On the inner faces of the clamping plates are sheets of insulating material 5. Clamped between plates A—A and insulated therefrom by insulation 5, is a series of overlapping or staggered plates or laminæ 6. The plates 6 are preferably made of metal and have a film or coating of high resistance material thereon. This coating is preferably of a metallic oxide nature and may be a natural film which forms during the production of the sheet metal plate from which the laminæ are cut, or it may be applied to the clean metal surface with a brush or spray or it can be formed by chemical action on a clean sheet metal plate. In practice, the laminæ are preferably formed from metallic sheets upon which a paper-like oxide coating is formed during the manufacture of the material. A four per cent silicon-iron forms such an oxide during the process of manufacture.

When the plates are superimposed as shown in Fig. 1, only a relatively small 85 area of the plate is in contact with the next adjacent plate, while the rest of the area of each plate provides a heat radiating surface. The resistance to electric currents is offered at the contacting surfaces and 90 in the coating, so that the greatest amount of heat is developed at the points of contact and in the overlapping layers or films of oxide between the plates. The oxide or other high resistance coating being in intimate contact with the laminæ, really comprising an integral part of the laminæ, the laminæ will receive the heat so produced and store it or radiate it. This will prevent overheating and the unit is therefore 95 a desirable one for use in starting a motor under a heavy load, or in other applications where a heavy current is to be controlled.

As shown in the drawings, the plates 105 A—A are clamped together by bolts 7 having nuts thereon and surrounded by an insulating sleeve 8. The plates or laminæ 6 may have notches cut therein to fit around the insulated bolts to prevent displacement 110

of the laminæ. I do not, however, limit myself to these details of construction. The connecting terminals are designated at 9 and 10.

5 Instead of flat plates being used, as shown in Fig. 1, conical plates or lamæ might be used, as shown in Figs. 3 and 4. In these figures, B—B are conical clamping plates having insulation 11 on the inner faces thereof. Laminæ of relatively large diameter are designated by 12, and 13 are laminæ of a relatively small diameter. Laminations 12 and 13 are alternately arranged between plates B—B. All of the laminations may be 10 coated or otherwise provided with a resistance material, as hereinbefore described or the laminæ 13 only may be of high resistance material, while laminations 12, by reason of their greater area, provide heat storage and 15 radiating means. Plates B—B may be clamped together by suitable means, as by bolts 14, having insulating sleeves 15 surrounding them. In order to give compactness to the unit, each of the laminæ 12 may 20 be notched to fit around the bolts. The terminals of the resistance unit are designated by numerals 16 and 17 and are insulated from clamping plates B—B.

Another modification is suggested in Figs. 30 6 and 7, in which C—C designate clamping plates having insulation 20 on their inner faces. Plates or laminations having a relatively large area are designated at 21, and 22 are laminations of a relatively small size. 35 Laminations 21 and 22 are alternately arranged between plates C—C so that the larger plates 21 are spaced apart. Plates 22 may be composed of a relatively high resistance substance, or they may be conducting 40 plates having a resistance coating, as hereinbefore described, as may also be the large plates 21. Plates C—C may be held together to clamp the laminations in position in any suitable way, as by bolts 23 having an insulating sleeve thereabout. The laminations 45 21 and 22 may be notched to engage the insulated sleeve around the bolts, if desired, to hold the plates in place, or the friction between the separate laminæ may be relied 50 upon. The terminals of the resistance unit are designated at 24 and 25.

The resistance of each unit may be 55 changed when necessary by adding or subtracting plates or laminæ, or, in the arrangement shown in Fig. 1, by adjusting the plates to vary the overlapping areas of the laminations. In any of the constructions shown, the heat radiating laminæ are in intimate contact with the resistance element, 60 and they provide a considerable capacity for the heat generated in the resistance. I am, of course, aware that certain forms of con-

tact resistances have heretofore been employed, and am also aware that rheostats having carbon, graphite, or other disks or 65 plates are in use, in which the resistance is varied by varying the pressure of the disks or plates against one another, but I am not aware that resistance units comprising a 70 laminated series of plates or other members, which may be of metal, carbon, graphite, or any other preferred material, having a high resistance element disposed between the laminæ and with the laminæ so arranged as to provide heat radiating surfaces, have 75 heretofore been used. The units may be designed for rugged and heavy use, and are well adapted to stand up under such use. The laminæ or plates themselves may be of a more or less resistant nature, as desired, this 80 depending on the material from which they are made.

Obviously, various changes may be made in the construction and design of the resistance unit within the contemplation of my invention and within the scope of the appended claims.

I claim:

1. A resistance unit comprising a laminated structure, the laminæ of which have 90 overlapping areas, and a relatively high resistance substance in the form of a film interposed between adjacent overlapping areas of the laminæ, said laminæ providing a capacity for heat generated in the inter- 95 posed relatively high resistance substance.

2. A resistance unit comprising a laminated structure composed of a series of members, each of which has a relatively large, exposed heat-radiating surface, and resistance 100 film applied to overlapping surfaces of said members.

3. A resistance unit comprising a laminated structure, the laminæ of which are of conducting material having overlapping 105 contacting surfaces on which is a film of relatively high resistance material, some of said laminæ having a relatively large surface area exposed for radiation of heat generated in said high resistance material. 110

4. A resistance unit comprising a laminated structure, the laminæ of which are formed of sheet metal having an oxide coating thereon, some of said laminæ having a relatively large exposed surface area for the 115 radiation of heat.

5. A resistance unit comprising a laminated structure, some of the laminæ of which are of a conducting material having a surface film of high resistance material through 120 which the current passes from one laminæ to the next.

In testimony whereof I affix my signature.
JOHN G. HOMAN.
